MEANS FOR PREPARING THE HEEL SEATS
OF INSOLES

Harry McGrory, Richmond Hill, N. Y.

Application December 10, 1940, Serial No. 369,398

11 Claims. (Cl. 12—31.5)

This invention relates to means for preparing the heel seats of insoles and has for its main object the provision of means for simultaneously cutting a strip from the heel seat part and to provide the latter with a beveled marginal edge portion whereby to improve the fit of the heel seat part of the insole at the heel seat of the shoe.

Another object of the invention is the provision of a device of the character described which can be utilized in cut-out machines which are readily available on the market.

A further object of the invention is to provide a device of the character described of such construction that it can be utilized for cutting and molding the heel seat parts of insoles of various sizes.

Another object of the invention is to provide the device with adjustable means for positioning the heel seat part of the insole in relation to the cutter.

The above objects of the invention and other objects which might hereinafter appear will be fully understood from the following description considered with reference to the accompanying illustrative drawing.

In the drawing:

Fig. 1 is a top view of a die cutter and mold embodying the present invention;

Fig. 2 is a bottom view thereof;

Fig. 3 is a sectional view on the line 3—3 of Fig. 1, and shows more or less diagrammatically the plunger which coacts with the die cutter and mold in the cut-out machine;

Fig. 4 is a top plan view on a larger scale of the die mold and cutter;

Fig. 5 is a sectional view on the line 5—5 of Fig. 4;

Fig. 6 is a top plan view of a part of the insole prepared with the device embodying the present invention;

Fig. 7 is an edge view of the insole illustrated in Fig. 6, the U-shaped strip being removed.

Referring now to the drawing in detail the device embodying the present invention comprises a rigid frame or bed plate 10 on which the unitary die cutter and mold 12 is mounted. Said unitary cutter and mold has a flat lower surface which rests on the flat upper surface of bed plate 10 and is held removably in stationary position on said bed plate by pins 13 fixed to and depending from the cutter and fitting into holes 13a in said bed plate. A plate 14 is supported for movement toward and away from the upper surface of bed plate 10, said plate being spring projected upwardly by a plurality of springs 16 disposed around pins 18, respectively, which are fixed to and depend from the bottom surface of plate 14 and extend into openings 20 in bed plate 10. Plate 14 is provided with an opening 22

which surrounds the die cutter and mold 12, the edge of said opening being spaced from said die cutter and mold. Said opening has a forward part 22a for the projection of the heel breast covering flap of the insole. When plate 14 is in upwardly projected position the lower surface of plate 14 is approximately at the same level as the upper edge of the die cutter.

The die cutter comprises a U-shaped cutter 24 having a U-shaped cutting edge 25 and laterally extending parts 26 each having a straight edge 27. Said parts 26 extend laterally and outwardly of the opposite legs, respectively, of the U-shaped cutting edge of the cutter. As shown said cutting edges 27 are disposed between the laterally spaced ends and the opposite end of said U-shaped cutting edge. When the heel part of the insole is subjected to the action of the cutting die a U-shaped strip 28 is cut therefrom by the part of the cutter extending from one lateral cutting part 26 rearwardly of the cutter around the back thereof and then forwardly to the other lateral extending cutting part 26, and in addition cuts 28b are formed in the insole forwardly by the parts of the cutting die which extend forwardly of the lateral cutting parts 26 to the laterally spaced ends, respectively, of said U-shaped cutting edge. The die cutter and mold includes a heel seat molding part 30 which is located at the inner side of die cutter 24, being seated in the recess 31 of cutter 24, and being secured in said recess by a screw 31a. Said molding part comprises a U-shaped ledge 32 which extends laterally of the inner surface of cutter 24 and is inclined downwardly from a point just below or inwardly of the top of the cutting edge of the cutter 24 to the central depressed portion 34 of the mold. When the plunger 36 (indicated diagrammatically) of the cut-out machine of any suitable type, for example, a Knight cut-out machine, is actuated, it brings the work-piece, in this case the heel part of the insole, into engagement with the die cutter and mold 12 for cutting the same and for shaping 45 and molding the heel seat portion of said insole to provide the latter with a beveled edge part 38 extending between the cut edge 39 and the inner part 40 indicated by the dotted line in Fig. 6. Further the central part 42 of the heel seat is 50 brought into a somewhat concave form on its upper surface. Thus, the heel seat part of the insole is provided with a beveled marginal edge portion extending completely around said part. The heel breast flap of the insole is indicated at 55 43 in Fig. 7.

Provision is made for positioning the insole on plate 14 in relation to the die cutter and mold 12. For this purpose adjustable positioning plates 44 are provided, said plates being movable toward and away from each other and from the

adjacent side edges of opening 22. Said plates are provided with pins 46 which project into guide slots 48 in plate 14 and with other pins 50 which project into guide slots 52 provided in said plate. Plates 44 are also provided with fixed pins 51 which engage plate 14 in guide slots 51a. A toggle lever composed of members 54 pivotally connected to pins 50 is provided for moving positioning plates 44 simultaneously. Said members 54 are pivotally mounted on pivot pins 56 fixed to and depending from the lower surface of plate 14 and have slots 58 in their outer ends which are arranged in crossed relation. A longitudinally movable rod 60 is provided with a pin 62 which passes through the slots 58 in both members 54 at the intersection thereof and rides in a longitudinally extending guide slot 64 provided in plate 14. One end of rod 60 has a threaded portion 66 which is engaged by a nut 68 threaded thereon, said nut projecting through an opening 70 in plate 14 and held against movement longitudinally of rod 60 whereby rotation of said nut is effective to move rod 60 without turning the latter. Rod 60 further is in engagement with a non-threaded guide lug 72 fixed to and projecting from the lower surface of plate 14 and with a non-threaded guide lug 74 which is also fixed to and projects from the lower surfaces of plate 14. Thus, by rotating nut 68 plates 44 can be readily adjusted for insoles of various sizes.

The position of the rear edge of the insole is determined by an adjustable plate 76 adjustably mounted on plate 14 at the rear of opening 22. Positioning plate 76 is provided with pins 78 and 80 which engage in guide slots 82 and 84, respectively, in plate 14. A wing nut 86 threaded on pin 78 is provided for securing positioning plate 76 releasably in adjusted position.

The manner of utilizing the above described device is largely apparent from the above description. It will be understood that a plurality of interchangeable unitary die cutter and mold members 12 can be provided to take care of insoles of various sizes. For this purpose all of said die cutter and mold members 12 are preferably provided with the pair of pins 13 thereof uniformly spaced for engagement with openings 13a in bed plate 10. In using the device of the present invention, the latter is mounted in a suitable cut-out machine such as, for example, a Knight cut-out machine, which is well known to shoe manufacturers, for coaction with the plunger 36 of said machine. The insole to be subjected to the action of the device is placed in position, the grain or upper surface of the insole uppermost and the heel seat part thereof resting on plate 14 over opening 22 therein in the position determined in advance by the adjustment of plates 44 and 76, the peripheral edge of the heel seat part of the insole engaging the adjacent edges of said plates 44 and 76. The heel breast covering flap 43 of the insole is projected through the front part 22a of opening 22 so that the marginal edge portion of the heel seat part lies flat on plate 14. When the insole is thus positioned on plate 14 the plunger 36 is depressed and engages the upper surface of the insole, clamping the latter to said plate, and forces the insole and the plate 14 downwardly in opposition to the action of springs 16, thereby bringing the heel seat part of the insole into engagement with the die cutter and mold 12 for cutting the U-shaped strip 28 therefrom, for providing the longitudinally extending cuts 28b, and for shaping the heel seat part of the insole by the action of mold

30 in conjunction with cutter 24 as described above.

While I have shown and described the preferred embodiment of my invention it will be understood that the latter may be embodied otherwise than as herein shown or described, and it will be also understood that in the illustrated embodiment certain changes in the details of construction and in the arrangement of parts may be made and will occur to skilled artisans in view of the present disclosure. Therefore, I do not wish to be limited to the form of the invention herein shown or described or to the details of construction thereof except to the extent which may be required by the scope of the appended claims.

Having thus described my invention, what I claim and desire to secure by Letters Patent is:

1. A device of the class described comprising a die cutter having a U-shaped cutting edge, and stationary means forming a molding surface disposed inwardly of and adjacent to the plane of said cutting edge, said die cutter having an inner surface terminating in said U-shaped cutting edge and said molding surface having a bounding edge abutting said inner surface of said die cutter.

2. A device of the class described comprising a die cutter having a U-shaped cutting edge, and means in fixed relation to said cutting edge forming a molding surface disposed inwardly of and adjacent to the plane of said cutting edge, said U-shaped cutting edge terminating in laterally spaced ends, and parts of said cutter disposed at the outer side thereof and having cutting edges extending laterally of the opposite legs, respectively, of said U-shaped cutting edge between said ends, respectively, thereof and the opposite end of said U-shaped cutting edge, said molding surface being in inclined relation to the plane of said U-shaped cutting edge and extending laterally of the inner side of said cutter.

3. A device of the class described comprising a die cutter having a U-shaped cutting edge, said cutter having parts provided with cutting edges, extending laterally and outwardly from the opposite legs of said U-shaped cutting edge inwardly of the free ends of the latter, and stationary means located at the inner side of said cutter and forming a molding surface disposed inwardly of and adjacent to the plane of said U-shaped cutting edge, said die cutter comprising a recessed member and said last mentioned means comprising a member fitting in said recess in fixed relation to said recessed member.

4. A device of the class described comprising a die cutter having a U-shaped cutting edge, said cutter having parts provided with cutting edges extending laterally and outwardly from the opposite legs of said U-shaped cutting edge inwardly of the free ends of the latter, and stationary means located at the inner side of said cutter and forming a molding surface disposed inwardly of and adjacent to the plane of said cutting edge, said molding surface being in inclined relation to the plane of said U-shaped cutting edge, and sloping downwardly from said cutting edge, the upper edge of said surface lying adjacent said cutting edge and conforming to the shape thereof.

5. A cutting device of the class described operable in conjunction with a plunger engageable with a work-piece to be cut, said device comprising a spring-projected plate having an opening, a die cutter having a cutting edge positioned in a plane adjacent the plane of said plate opening,

said plate being constructed and arranged to support the work-piece to be cut by said die and to be moved under the action of said plunger relatively to said die in a direction inwardly of said cutting edge so that the latter projects outwardly through said plate opening for cutting said work-piece, and means located at the inner side of said cutter and positioned inwardly of the plane of said cutting edge operable in conjunction with said cutter and said plunger for molding a marginal portion of the work-piece adjacent the cut edge thereof, said die cutter comprising a recessed member and said last mentioned means comprising a member fitting in said recess in fixed relation to said recessed member.

6. A cutting device of the class described operable in conjunction with a plunger engageable with a work-piece to be cut, said device comprising a spring-projected plate having an opening, a die cutter having a U-shaped cutting edge positioned in a plane adjacent the plane of said plate opening, said plate being constructed and arranged to support the work-piece to be cut by said die and to be moved under the action of said plunger relatively to said die in a direction inwardly of said cutting edge so that the latter projects outwardly through said plate opening for cutting said work-piece, means located at the inner side of said cutter and positioned inwardly of the plane of said cutting edge operable in conjunction with said cutter and said plunger for molding a marginal portion of the work-piece adjacent the cut edge thereof, said U-shaped cutting edge terminating in laterally spaced ends, and parts of said cutter disposed at the outer side thereof and having cutting edges extending laterally of the opposite legs, respectively, of said U-shaped cutting edge between said ends, respectively, thereof and the opposite end of said U-shaped cutting edge.

7. A cutting device of the class described operable in conjunction with a plunger engageable with a work-piece to be cut, said device comprising a spring-projected plate having an opening, a die cutter having a U-shaped cutting edge positioned in a plane adjacent the plane of said plate opening, said plate being constructed and arranged to support the work-piece to be cut by said die and to be moved under the action of said plunger relatively to said die in a direction inwardly of said cutting edge so that the latter projects outwardly through said plate opening for cutting said work-piece, and means located adjacent the inner surface of said die cutter forming a molding surface disposed inwardly of and adjacent to the plane of said cutting edge, said die cutter comprising a recessed member and said last mentioned means comprising a member fitting in said recess in fixed relation to said recessed member.

8. A cutting device of the class described operable in conjunction with a plunger engageable with a work-piece to be cut, said device comprising a spring-projected plate having an opening, a die cutter having a U-shaped cutting edge positioned in a plane adjacent the plane of said plate opening, said plate being constructed and arranged to support the work-piece to be cut by said die and to be moved under the action of said plunger relatively to said die in a direction inwardly of said cutting edge so that the latter projects outwardly through said plate opening for cutting said work-piece, and means located adjacent the inner surface of said die cutter form-

ing a molding surface disposed inwardly of and adjacent to the plane of said cutting edge, said molding surface being in inclined relation to the plane of said cutting edge and sloping downwardly from the inner side of said U-shaped cutting edge.

9. A cutting device of the class described operable in conjunction with a plunger engageable with a work-piece to be cut, said device comprising a spring-projected plate having an opening, a die cutter having a cutting edge positioned in a plane adjacent the plane of said plate opening, said plate being constructed and arranged to support the work-piece to be cut by said die and to be moved under the action of said plunger relatively to said die in a direction inwardly of said cutting edge so that the latter projects outwardly through said plate opening for cutting said work-piece, and means on said plate for

20 positioning the work-piece thereon in relation to said cutter, said positioning means comprising members mounted on the upper surface of said plate for movement at opposite sides of said opening toward and away from each other and toward and away from the adjacent edges of said opening.

10. A cutting device of the class described operable in conjunction with a plunger engageable with a work-piece to be cut, said device comprising a spring-projected plate having an opening, a die cutter having a cutting edge positioned in a plane adjacent the plane of said plate opening, said plate being constructed and arranged to support the work-piece to be cut by said die and to

25 be moved under the action of said plunger relatively to said die in a direction inwardly of said cutting edge so that the latter projects outwardly through said plate opening for cutting said work-piece, means on said plate for positioning the work-piece thereon in relation to said cutter, said positioning means comprising members mounted on said plate for movement at opposite sides of said opening toward and away from the adjacent edges of said opening, and means for moving said

40 members simultaneously.

11. A cutting device of the class described operable in conjunction with a plunger engageable with a work-piece to be cut, said device comprising a spring-projected plate having an opening, a die cutter having a cutting edge positioned in a plane adjacent the plane of said plate opening, said plate being constructed and arranged to support the work-piece to be cut by said die and to be moved under the action of said plunger relatively to said die in a direction inwardly of said cutting edge so that the latter projects outwardly through said plate opening for cutting said work-piece, means on said plate for positioning the work-piece thereon in relation to said cutter, said

60 positioning means comprising members mounted on said plate for movement at opposite sides of said opening toward and away from the adjacent edges of said opening, means for moving said

65 members simultaneously comprising a pair of lever members connected to said positioning members, respectively, said lever members having slotted end portions arranged in crossed relation, and a longitudinally movable rod having a part projecting into said slotted end portions at the intersection thereof whereby longitudinal movement of said rod is effective to actuate said lever members.

HARRY McGRORY.
